BUMPER FOR AN AUTOMOBILE OR THE LIKE

Irvin W. Rybicki, Birmingham, Mich., assignor to General Motors Corporation, Detroit, Mich., a corporation of Delaware

Filed May 23, 1960, Ser. No. 60,684

Term of patent 7 years

(Cl. D14—6)

FIGURE 1 is a front elevational view of a bumper for an automobile or the like showing my new design;

FIGURE 2 is a top plan view;

FIGURE 3 is a side elevational view;

FIGURE 4 is a sectional view taken generally along the plane indicated by line 4—4 of FIGURE 1, and;

FIGURE 5 is a perspective view.

The broken line showing of the automobile and portions thereof is for purposes of illustration only.

The characteristic features of my design for the bumper disclosed reside in the downwardly and outwardly extending side wing portions thereof as best shown in FIGURES 1 and 3.

I claim:

The ornamental design for a bumper for an automobile or the like, substantially as shown and described.
